G. A. CANNING

TOOL FOR REMOVING AUTOMOBILE HEADLIGHTS

Filed Dec. 4, 1922

INVENTOR

George A. Canning

BY Chapman & Neale

ATTORNEYS

UNITED STATES PATENT OFFICE.

GEORGE A. CANNING, OF SOUTH DEERFIELD, MASSACHUSETTS.

TOOL FOR REMOVING AUTOMOBILE HEADLIGHTS.

Application filed December 4, 1922. Serial No. 604,958.

To all whom it may concern:

Be it known that I, GEORGE A. CANNING, citizen of the United States, residing at South Deerfield, in the county of Hampshire and State of Massachusetts, have invented new and useful Improvements in Tools for Removing Automobile Headlights, of which the following is a specification.

This invention relates to wrenches of the 10 type adapted to frictionally embrace circular objects and more particularly to wrenches for embracing and removing the rims or lens holders of automobile headlights and the like.

15 An object of the invention is to provide a device that may be easily and quickly applied to an object such as a headlight rim that is constructed and arranged so that it will not injure the rim during the clamping 20 action.

Another object of the invention is to provide a simple device by reason of which its manufacturing cost is greatly lessened.

The form of the invention as at present 25 preferred is shown in the accompanying drawings in which:—

Fig. 1 is a side elevational view of the device;

30 Fig. 2 is a sectional elevation taken on the line 2—2 of Fig. 1;

Fig. 3 is a cross-sectional view taken on the line 3—3 of Fig. 1;

Fig. 4 is a cross-sectional view taken on the line 4—4 of Fig. 1; and

35 Fig. 5 is a fragmentary plan view of the perforated end of the flexible strip.

Referring to the drawing in detail the device comprises a band or strip 1 preferably of a flexible and resilient material 40 such as spring steel or the like that is adapted to conform to the circular shape of the article around which the band is to be bent. The end 2 thereof is provided with a plurality of perforations or openings 3 which in 45 this case are shown as being circular in shape but which, may be of any shape desired and are provided for the purpose as will later appear.

A block 5 is fixed to the underside of 50 the strip 1 by rivets 6 or the like and is provided in its upper side with a U-shaped recess 8 that serves as a bearing for the handle H. The under side 7 of the block 5 is curved to conform to the circular contour of a headlight rim and its purpose is 55 to distribute the pressure upon the rim dur-

ing the clamping and removing operation. A friction lining 9 is secured to the inner surface of the band 1 and block 5 by any suitable means such as rivets and preferably 60 is of a resilient or yieldable material such as rubber or other material that is adapted to be bent to conform to the shape of a lamp rim, and that is capable of frictionally engaging the rim.

65 An operating handle H is provided, the lower end of which is bifurcated in the form of two separated side portions 10 that are separated a sufficient distance to embrace the block 5. A pivot member 11 connects the portions 10 at the lower ends thereof and is adapted to rest in the U-shaped slot 8 of the block and is held therein by the band 1 as best shown in Fig. 1. A transverse cylindrical member 12 is also connected to the portion 10 and serves to support the strip 1 and bolt B.

70 The upper end of the handle H is preferably semi-circular in cross-section as best shown in Figs. 3 and 4 and is provided with 80 transverse webs 14 that are notched as at 14' to receive and guide the bolt B. A slot 13 is provided in one side of the handle to limit the movement of the bolt B and a web 19 in the upper end thereof serves as an 75 abutment for the spring 18.

85 The bolt B is preferably rectangular in cross-section and fits loosely within guides 14' of the webs 14 of the handle and is adapted for a longitudinal movement therein. Its lower end is preferably cylindrical in cross-section as at 15 and is adapted to enter and engage the circular openings 3 of the strip 1. A head 16 carried by the bolt slides within the slot 13 of the handle and is riveted or spun upon its outer end to hold the bolt in place in its guides. A knob 17 is provided on the forward side of the bolt by the means of which the bolt may be manually moved upwardly and out of engagement with the perforations of the strip. A compression spring 18 is interposed between the upper end of the bolt B and web 19 of the handle and functions to normally hold the bolt in the strip 100 engaging position shown in Fig. 1.

105 In general the device is adapted for embracing various circular objects but as before stated is particularly applicable for engaging and removing the rims of head lights 110 and its operation will now be described in connection therewith. In removing a head-

light rim the flexible band or strip 1 is laid around the rim and with the bolt B being withdrawn the perforated end 2 of the band is passed between the bifurcated 5 end of the handle and over the bar 12. When the band is pulled snugly around the rim the handle knob 17 is released to allow the spring 18 to force the bolt downward so that its end 15 may engage an opening 10 3 of the strip end 2. When thus so adjusted the handle H is moved to the right which movement causes the band to tightly and frictionally embrace the head lamp rim and move the same in the direction of the 15 handle movement. The block 5 by reason of its inner curved surfaces bears upon a considerable portion of the rim and distributes the thrust of the pivot 11 about the rim of the head lamp and therefore prevents the rim becoming dented or otherwise 20 injured.

Having described my invention what I desire to claim is—

1. A head lamp wrench comprising in 25 combination, a flexible strip having one of its ends perforated, a block fixed to the other end of said strip having a U-shaped slot in the upper side thereof that underlies the said strip to provide a bearing therewith, 30 a handle having bifurcated ends that are connected with a pivot member that interfits the said bearing and a transverse bar

that is adapted to support the end of the said strip, a bolt member slideable in the said handle that is adapted to abut the transverse bar and to engage the perforations of the strip, a spring carried by the handle that acts upon the bolt tending to normally hold the said bolt in its strip engaging position, and a strip of yieldable 40 material fixed to the under side of the flexible strip and block.

2. A head lamp wrench comprising in combination, a flexible strip having a perforated end, a block fixed to the other end of the said strip having a U-shaped recess in the upper side thereof that underlies the said strip to form a bearing therein, a handle having bifurcated ends that straddle the said block and that are connected by a pivot 45 that interfits the said bearing and a transverse member for supporting the perforated end of said strip, a bolt slideable within the handle for engaging the perforation of said strip that abuts the said transverse bar, that is provided with a projection, the said handle being provided with a slot to receive the projection of the bolt to limit the relative movement thereof, and a spring carried by the handle that tends to move the said bolt 50 to its strip engaging position.

In testimony whereof I have affixed my signature.

GEORGE A. CANNING.
